COMBINATION SQUARE HEAD AND RULE

Ernest Keszler, 3525 Broadway, Chicago, Ill.

Filed Sept. 11, 1961, Ser. No. 66,694

Term of patent 14 years

(Cl. D52—6)

FIG. 1 is a perspective view of a combination square head and rule, showing my new design;

FIG. 2 is a top plan view thereof;

FIG. 3 is a left end elevational view thereof;

FIG. 4 is a right end elevational view thereof; and

FIG. 5 is an enlarged fragmentary perspective view thereof.

The opposite side of the rule portion is substantially the same as the side shown.

The combination square head and rule is characterized by the curved vernier scale element at the top of the

square head in association with the particularly shaped aperture just beneath same.

I claim:

The ornamental design for a combination square head and rule, as shown and described.
